UNITED STATES PATENT OFFICE.

HORACE GRIFFIN, OF NEW HAVEN, CONNECTICUT.

LETTER-COPYING PRESS.

SPECIFICATION forming part of Letters Patent No. 339,643, dated April 13, 1886.

Application filed January 18, 1884. Serial No. 117,958. (No model.)

To all whom it may concern:

Be it known that I, HORACE GRIFFIN, a citizen of the United States, residing at New Haven, in the county of New Haven and State of Connecticut, have invented certain new and useful Improvements in Letter-Copying Presses; of which the following is a specification, reference being had therein to the accompanying drawings.

10 This invention relates to portable copying presses, wherein the platen is operated through the medium of a lever.

According to this invention, the base-plate has at each end an upwardly-extending standard or plate provided with flanged ends or guideways, and the top plate is supported in position at each end between inwardly-projecting lugs on plates, which fit and slide vertically within the flanged ends of the standard attached to the base. On the outer face of each sliding plate are notches or pins with which a disk engages, in order that upon turning said disks in one direction said plates and the thereto-connected top plate of the press will be raised, while by turning said disks in the opposite direction said parts will be lowered for the purpose of regulating the height of the space between the base and top of the press, and thereby adapting the press for use 30 with books of different thicknesses. The platen is separate from the top plate of the press, and is centrally attached to the lower end of a plunger, which extends upward through the top plate of the press, and has pivoted thereto one end of a lever, which is centrally journaled within standards attached to the top plate, the opposite end of said lever extending across the path of and being raised by a cam mounted upon a cross-shaft, which is journaled in other standards attached to the top plate, and on which shaft the lever or handle for operating the platen is mounted. The platen is supported and returned to its highest position, upon the handle being turned to 45 throw out of operating position, by means of springs whose inner ends are attached to suitable bosses or pins on the inner faces of the plates supporting the top plate of the press, or in other convenient position.

50 In the drawings, Figure 1 represents a perspective view of my improved copying-press. Fig. 2 is a side elevation with the parts

raised in readiness to receive a book, the top plate being shown in section. Fig. 3 is a sectional end view. Fig. 4 represents in detail 55 a perspective view of the cam and shaft thereof. Fig. 5 represents an elevation of a portion of the sliding plate on which the top plate of the press is supported. Fig. 6 represents an elevation of the inner face of one of the disks 60 for operating the sliding plates. Fig. 7 represents in vertical elevation one of the vertical standards attached to the base-plate, one of the vertical sliding plates, and a modified form of disk for raising and lowering said vertical 65 sliding plates.

A denotes the base-plate of my press, said base-plate being provided at its ends with transverse standards B, having guideways C at their ends.

70 D is the top plate of the press, said top plate being supported by vertical end plates, G, having flanges E, by which they are attached to the top plate. The plates G are provided on their outer faces with lugs or teeth H, engaged by volute or spiral threads J on disks I, said disks being journaled in the standards B, and having thumb-pieces a, by which they may be turned, the plates G having slots K, through which the journals of said disks pass, thus 75 permitting the plates G to be adjusted vertically on the stationary standards B. When the disks I are turned in one direction, the spiral threads or coils on the inner faces of said disks will engage with the teeth H, and by their cam-like action upon said teeth will force said plates, with the thereto-attached top plate of the press, upward, and thus increase 80 the depth of the opening within which the book or other article to be pressed is received, 90 while by turning said disks in the reverse direction the spiral threads or coils on said disks will operate to draw down the top plate whenever it may be desired to decrease the vertical space within which the book is placed. 95 The vertical slots K in the plates G permit of the free vertical movement thereof.

M represents the platen, which is formed separately from the top plate of the press and has movement independent thereof.

100 N represents springs, which at their rear ends are attached, either to lugs or pins on the inner faces of the plates G, as shown in Fig. 3, to the standards B, as shown in Fig. 2, or to the top

plate of the press, as may be most convenient, their free ends extending to and impinging against the under face of the platen at each end, for the purpose of affording to said platen 5 a yielding support, which, while sufficient to hold said platen in its position of rest, also serves to steady the same during its downward movement.

O represents a plunger, which passes through 10 a hole, b, in the top plate, D, its lower end passing centrally through and being riveted to the under face of said platen. This plunger has at its upper end an enlargement or head having ears P, each having a hole, c, and Q represents a lever adapted to rest and work between said ears. A short shaft, d, passes through said ears, and through a hole in the rear end of said lever, for the purpose of pivotally securing said lever within said ears. 15 This lever Q is centrally pivoted, by means of a short shaft, e, between ears or standards R, extending upwardly from the casting S, attached to the top face of the top plate, D. The free end of this lever Q extends in a curvi- 20 linear direction to the top of other ears or standards, T, extending upwardly from the casting S.

u represents a shaft having bearing transversely within the standards T, and on said shaft is a cam, V, which works between said ears 30 as said shaft is rotated. This shaft at one end extends outward beyond the ears T, and has keyed thereto a handle or lever, W.

In Fig. 7 I have shown a modification of my device for raising and lowering the end plates 35 and top plate of the press. In this arrangement, instead of the notches or teeth H on the outer faces of plates G, I attach thereto a pin, f, and in lieu of the disk having spiral threads or coils on its inner face, I form the disk with 40 a cam-slot, g, so that as said disk is rotated in one direction the said slot will operate upon one face of the pin f so as to force the sliding plate G upward, and on turning said disk in the reverse direction will operate upon the op- 45 posite face of said pin and draw down the sliding plate G. Upon raising the handle or lever W the shaft u will be rotated so as to bring the enlarged portion of the cam up beyond the top of the ears or standards T, and as said cam 50 rises it pushes up the curvilinear end of the lever Q, and as such end of the lever Q rises its opposite end will, by reason of its central piv-

otal connection, be forced downward, and as it passes downward it will force down the plunger and the thereto-attached platen, and thus 55 press the book or other article placed between the base-plate and the platen. The reverse movement of the lever or handle W will return the cam to its lowest position, and as the downward pressure of the plunger is released the springs N will force the platen upward to its position of rest and permit of the withdrawal of the pressed article.

X represents a hollow block attached to the casting S or top plate of the press beneath the 60 eccentric V, and containing a lubricant or packing, a', in which the eccentric V works, so as to insure the easy movement thereof.

Having thus described my invention, what I claim is—

1. The combination, with a platen, of a plunger attached thereto, a lever attached at its rear end to said plunger and having a central pivotal bearing, a cam adapted to operate upon said lever to force the plunger downward, 75 and a lever or handle attached to the cam-shaft for the purpose of oscillating the same, substantially as set forth.

2. In a copying-press, the combination, with a base-plate provided at its ends with transverse standards having guideways at their ends, of a top plate, vertical end plates attached to said top plate and having teeth or projections, and rotary disks adapted to engage said 80 projections and thus support and adjust said end and top plates, substantially as set forth.

3. In a copying-press, the combination, with a base-plate having transverse standards provided with guideways at their ends, of a top plate, vertical end plates attached to said top plate and having lugs or teeth on their outer faces, and rotary disks journaled in said standards and having on their inner faces spiral threads engaging said lugs or teeth, said disks being provided with thumb-pieces, by which they may be conveniently turned to adjust end plates and the top plate sustained thereby, 90 substantially as set forth.

In testimony whereof I affix my signature in presence of two witnesses.

HORACE GRIFFIN.
